Primary Examiner — Susan Bennett Hattan*Assistant Examiner* — Suzanne E Tisdell(74) *Attorney, Agent, or Firm* — Crowell & Moring LLP(57) **CLAIM**

The ornamental design for a door for a vehicle, as shown and described.

DESCRIPTION

This application contains subject matter related to the following co-pending U.S. design patent applications:

Application Ser. No. 29/624,716, filed herewith and entitled “Vehicle, Toy, and/or Replicas Thereof”;

Application Ser. No. 29/624,718, filed herewith and entitled “Vehicle, Toy, and/or Replicas Thereof”;

Application Ser. No. 29/624,728, filed herewith and entitled “Door for a Vehicle”; and

Application Ser. No. 29/624,730, filed herewith and entitled “Door for a Vehicle”.

FIG. 1 is a front view of a door for a vehicle according to the design;

FIG. 2 is a left, front perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.
